UNITED STATES PATENT OFFICE.

JONAS MICHAEL HULTQVIST, OF STOCKHOLM, SWEDEN.

TREADLE.

SPECIFICATION forming part of Letters Patent No. 247,356, dated September 20, 1881.

Application filed June 2, 1881. (No model.)

To all whom it may concern:

Be it known that I, JONAS MICHAEL HULTQVIST, of Stockholm, Sweden, have invented certain useful Improvements in Treadles, of which the following is a specification.

The object of my invention is to provide a new and improved treadle for sewing-machines, lathes, band sawing-machines, &c., which can be operated more conveniently than the treadles in use heretofore, and with less strain on the operator.

The invention consists in a treadle whose foot-board rests upon bracket-shaped supports journaled on the shaft and projecting a short distance above the same, said supports being attached to the foot-board, about one-third of the length of the latter from the heel end. The connecting-rod is pivoted to a downward-projecting arm of the front end of the foot-board.

In the accompanying drawings, Figure 1 represents a central vertical section of my improved treadle, and Fig. 2 a vertical section of the same through the line α α of Fig. 1.

The foot-board A of a treadle rests on bracket-shaped supports B, attached to the under side of the same, and loosely mounted on a rigid shaft, C, of the frame D, or these bracket-shaped supports B are rigidly mounted on the shaft C, which must then be journaled in the frame D. These bracket-shaped supports are about two to three inches high, and consequently the shaft C must be located lower than it is ordinarily, so that the foot-board will not be too high. The bracket-shaped supports B are attached to the foot-board about one-third of the length of the foot-board from the heel end of the same. The foot-board is provided at its front end with an outward and downward projecting arm, E, to the end of which the connecting-rod F is pivoted. When the foot-board is in a horizontal position the crank of the fly-wheel G will be in its lowest position, and consequently the front of the foot will

never have to be bent downward, and as the foot-board is not pivoted in the middle, but nearer the heel part, a considerable stroke of the front part of the foot-board can be obtained by depressing the heel part a very short distance only.

It is much less tiresome to press upon the foot-board with the heel than with the front of the foot, and with this improved treadle but a very slight movement of the foot is required.

As less power is required to operate this treadle than to operate the treadles in use heretofore this treadle can be operated much more rapidly.

One of the great advantages of this treadle is that the front end of the foot need not be bent downward, as this movement of the foot is very apt to cause cramps.

Having thus fully described my invention, I claim as new and desire to secure by Letters Patent—

1. A treadle made, substantially as herein shown and described, with the foot-board raised a short distance above the shaft, as and for the purpose set forth.

2. In a treadle, the combination, with the foot-board A and the shaft C, of the bracket-shaped supports B, attached to the foot-board at or near the rear third of the same, substantially as herein shown and described, and for the purpose set forth.

3. In a treadle, the combination, with the foot-board A and the shaft C, of the bracket-shaped supports B, arm E, projecting downward and outward from the front of the treadle, and of the connecting-rod F, pivoted to this arm E, substantially as herein shown and described, and for the purpose set forth.

JONAS MICHAEL HULTQVIST.
